UNITED STATES PATENT OFFICE.

ALEXIS ROSEN, OF PHILADELPHIA, PENNSYLVANIA.

BACK-PRESSURE AND EXHAUST RELIEF-VALVE.

1,054,034.

Specification of Letters Patent. Patented Feb. 25, 1913.

Application filed December 27, 1911. Serial No. 668,163.

To all whom it may concern:

Be it known that I, ALEXIS ROSEN, a subject of the Czar of Russia, having resided in the United States for one year last past 5 and having declared my intention of becoming a citizen thereof, residing in the city and county of Philadelphia, State of Pennsylvania, have invented a new and useful Back-Pressure and Exhaust Relief-Valve, 10 of which the following is a specification.

My invention consists of an improved back-pressure valve for conduits for fluid under pressure, in which the area of the fluid passage is regulated according to the 15 pressure of the fluid.

It further consists of improved means for controlling such regulation.

It further consists of improved means for checking the shock of the valve closing under reduced pressure or back-pressure. 20

It further consists of other novel features of construction, all as will be herein-after fully set forth.

The annexed drawings and the following 25 description set forth in detail one mechanical form embodying the invention, such detail construction being but one of various mechanical forms in which the principle of the invention may be used.

30 In said annexed drawings—Figure 1 represents a side elevation of my improved valve-mechanism. Fig. 2 represents an axial section of the same. Fig. 3 represents a transverse section on the line $\alpha-\alpha$ in Fig. 35 2. Fig. 4 represents a detail view of another form of adjustable counter-pressure device for the valve.

Similar numerals of reference indicate corresponding parts in the figures.

40 Referring to the drawings, the reference numeral 1 indicates a casing, cylindrical for the greater portion of its length and formed with an outwardly extending flange, 2, at its inlet end and contracted at its outlet end 45 to form a neck, 3, having a flange, 4, for connecting it to an exhaust pipe or other discharge means. A bottom, 5, is secured by bolts, 6, and nuts, 7, to the wide flange of the casing, and said bottom has a tubular 50 neck, 8, having a flange, 9, to which a pipe or other conduit for fluid may be connected. This neck is continued from the inner face 55 of the bottom by a cylinder, 10, of slightly larger interior diameter than that of the neck to form an annular shoulder, 11, at the outer end of the cylinder. The wall of the

cylinder is formed with an annular port, comprising a series of openings, 12, a short distance from the bottom, and the combined area of said openings is preferably greater 60 than the area of the inlet-passage through the neck. A piston, 13, preferably hollow and with a closed outer end, and formed with circumferential grooves, 14, in which packing-rings, 15, are placed, is fitted to 65 slide in the cylinder. A pin, 16, is secured diametrically through the piston, and a connecting rod, 17, has one end pivoted upon such pin. A rock-shaft, 18, is journaled in a bearing, 20, near the outlet end of the casing, and a crank, 21, is secured to the inner end of said shaft and has the other end of the connecting rod pivoted to its pin, 22. Said crank is of such length that the piston 70 will just cover the ports in the cylinder 75 when the crank stands forty-five degrees (45°) away from the axial line of the cylinder. A bell-crank, 23, is secured to the outer end of the rock-shaft and has an arm, 24, projecting at an angle of one hundred 80 and thirty-five degrees (135°) to the crank. A chain 25, preferably of the link or bicycle chain type, is connected to the outer end of said bell-crank arm and to a stud, 26, upon the side of the casing, and is of such length 85 that it will be straightened and stop rocking of the rock-shaft when the piston barely touches the annular shoulder in the cylinder. A spring, 27, is attached to the outer end of the other arm, 28, of the bell-crank, 90 which arm preferably stands at an angle of one hundred and thirty-five degrees (135°) to the former arm, and the other end of said spring is attached to a yoke, 29, secured to the ends of rods, 30, slidable in bearings, 31, 95 in the flange of the casing and connected at their ends by another yoke, 32. A screw, 33, having a suitable handle such as a wheel, 34, for turning it, is threaded through said latter yoke and has its cylindrical end, 35, 100 stepped in a bearing, 36, in the flange.

For the purpose of preventing the packing-rings from turning in the grooves in the piston, the inner face of each of said rings is provided with a shallow slot, 37, 105 which is engaged by the head of a screw, 38, in the bottom of the packing-groove in the piston.

In Fig. 4 of the drawings is illustrated another form of counter-pressure device, 110 in which the arm 28 of the bell-crank is extended and has a counter-weight, 39,

slidable upon it and adjusted by means of a set-screw, 40. This form may be preferable where the pressure is considerable and the pull of a spring not sufficiently 5 strong to counteract the same.

The bottom of the annular space between the cylinder and the casing has a channel, 41, closed by a removable screw-plug, 42, and condensed water may be withdrawn 10 through such channel by removing the plug.

Fluid-pressure entering the inlet will act against the closed end of the piston and move the same to overcome the counter-pressure of the spring or weight, and will 15 thus gradually uncover the annular port and allow the fluid to enter the annular space between the cylinder and casing, whence it will pass out through the outlet and be suitably disposed of. As the area of 20 the annular port is greater than that of the inlet, there will be less fluid-pressure within the casing than against the piston, owing to the expansion of the fluid, so that 25 the fluid acting against the piston acts only against the adjustable counter-pressure. If any back-pressure occurs by diminution of pressure on the inlet side or increase of pressure at the outlet side of the piston, the counter-pressure device will move the 30 piston to either partly or entirely close the annular port in the cylinder, and such back-pressure cannot reenter the source of the fluid, but will be shut off from such return. The counter-pressure may be adjusted by 35 means of the screw, when the spring is employed, and by shifting the counter-weight, when the latter is used. The shock caused by the sudden return of the piston will be borne by the bell-crank arm, the 40 chain and the stud upon the casing, so as to prevent injury to the piston by striking the annular shoulder. By placing the stop-mechanism for the valve exteriorly of the casing and valve-chamber, all injury to the 45 valve-piston and its cylinder by the shock of the closing valve-piston will thus be avoided, and the mechanism is accessible for adjustment or repair without the necessity of access to the interior of the casing. 50

This device is applicable to the exhaust-pipes of steam engines and to all other fluid conduits whether such fluid be gaseous or liquid.

55 Other modes of applying the principle of my invention may be employed for the mode herein explained. Change may therefore be made as regards the mechanism thus disclosed, provided the principles of construction set forth, respectively, in the following claims are employed.

Having thus described my invention, what I claim as new and desire to secure by Letters Patent, is:—

65 1. A device of the character stated, com-

prising a casing having an inlet and an outlet, a cylinder within said casing and communicating at one end with said inlet and formed at said end with an annular port, a closed piston reciprocable within said cylinder and across said port, adjustable pressure-means connected to the piston to force the same to close the port, and separate means exterior of the casing and connected to the piston to stop the closing movement 70 of the same. 75

2. In a device of the character stated, a casing having an inlet and an outlet, a cylinder within said casing and communicating at one end with said inlet and formed at 80 said end with an annular port, a closed piston reciprocable in said cylinder and across said port, adjustable resilient pressure-means connected to said piston to force the same to close the port, and flexible means 85 connected to said piston and rigidly secured to the casing to stop the closing movement of the piston.

3. In a device of the character stated, a substantially cylindrical casing having an 90 inlet at one end and an outlet at the other end, a cylinder extending in said casing from the inlet and having an annular series of openings through its wall at said end, a hollow piston having a closed end and reciprocable in said cylinder and over said 95 openings, a rock-shaft journaled in the casing and having a crank at its inner end, a connecting rod pivotally connected to said crank and to the piston, an arm secured to 100 the outer end of the rock-shaft, and a spring connected to said arm.

4. In a device of the character stated, a substantially cylindrical casing having an inlet at one end and an outlet at the other 105 end, a cylinder extending in said casing from the inlet and having an annular series of openings through its wall at said end, a hollow piston having a closed end and reciprocable in said cylinder and over said 110 openings, a rock-shaft journaled in the casing and having a crank at its outer end, a connecting rod pivotally connected to said crank and to the piston, an arm secured to the outer end of the rock-shaft, a spring 115 connected to said arm, and means for adjusting the tension of said spring.

5. In a device of the character stated, a substantially cylindrical casing having an inlet at one end and an outlet at the other 120 end, a cylinder extending in said casing from the inlet and having an annular series of openings through its wall at said end, a hollow piston having a closed end and reciprocable in said cylinder and over said 125 openings, a rock-shaft journaled in the casing and having a crank at its outer end, a connecting rod pivotally connected to said crank and to the piston, an arm secured to the outer end of the rock-shaft, a spring 130

connected to said arm, a yoke having the other end of said spring attached to it, rods guided upon the casing and having said yoke secured to their ends, a yoke secured 5 to the opposite ends of said rods, and a screw having its ends stepped in a bearing upon the casing and threaded through said last yoke.

6. In a device of the character stated, a 10 substantially cylindrical casing having an inlet at one end and an outlet at the other end, a cylinder extending in said casing from the inlet and having an annular series of openings through its wall at said end, a 15 hollow piston having a closed end and reciprocable in said cylinder and over said openings, a rock-shaft journaled in the casing and having a crank at its inner end, a connecting rod pivotally connected to said 20 crank and to the piston, a bell-crank secured upon the outer end of said shaft, a spring connected to one arm of said bell-crank, and a chain secured to the casing and connected to the other arm of the bell-crank.

25 7. In a device of the character stated, a substantially cylindrical casing having an outlet opening at one end and a flange at

the other end, a bottom secured to said flange and having a central inlet neck and a cylinder extending into the casing and 30 formed with an annular series of openings near the bottom and an internal annular shoulder, a hollow piston having a closed end and fitted to slide in the cylinder, a pin transversely secured in the piston, a connecting rod pivoted upon said pin, a rock-shaft journaled in a bearing in the casing near the outlet end, a crank secured upon the inner end of said rock-shaft and having the connecting-rod pivoted upon its pin, a 40 bell-crank secured upon the outer end of the rock-shaft, a spring connected to one arm of said bell-crank, rods sliding in the flange of the casing and having a yoke at their ends to which the spring is attached and a yoke 45 at the other ends, a screw threaded through said latter yoke and stepped in the flange of the casing, and a chain secured at one end to a stud on the casing and at the other end to the other arm of the bell-crank.

ALEXIS ROSEN.
